UNITED STATES PATENT OFFICE.

EARL UNDERWOOD, OF NEW YORK, N. Y., ASSIGNOR TO KREMENTZ & CO., A COPARTNERSHIP OF GEORGE KREMENTZ AND CARL H. LEBKUECHER, OF NEWARK, NEW JERSEY.

DESIGN FOR A CUFF-BUTTON TRAY.

45,438.

Specification for Design.

Patented Mar. 17, 1914.

Application filed November 17, 1913. Serial No. 801,540. Term of patent 7 years.

To all whom it may concern:

Be it known that I, EARL UNDERWOOD, a citizen of the United States, residing at New York, in the county of New York and State of New York, have invented a new, original, and ornamental Design for a Cuff-Button Tray, of which the following is a specification, reference being had to the accompanying drawing, forming part thereof.

The figure is a perspective plan view of a cuff button tray showing my new design.

I claim,

The ornamental design for a cuff button tray, as shown.

EARL UNDERWOOD.

Witnesses:

W. C. PEARSON,
E. V. FARNSWORTH.
